(57) CLAIM

The ornamental design for a touch table, as shown and described.

DESCRIPTION

FIG. 1 is a perspective view of the touch table showing my new design;

FIG. 2 is a top plan view of the touch table of FIG. 1;

FIG. 3 is a side elevational view of the touch table of FIG. 1; FIG. 4 is another side elevational view of the touch table of FIG. 1;

FIG. 5 is yet another side elevational view of the touch table of FIG. 1;

FIG. 6 is a perspective view of another embodiment of the touch table showing my new design;

FIG. 7 is a top plan view of the touch table of FIG. 6;

FIG. 8 is a perspective view of another embodiment of the touch table showing my new design; and,

FIG. 9 is a top plan view of the touch table of FIG. 8.

Broken lines shown in the drawings illustrate portions of the touch table, and form no part of the claimed design.
